(57) **CLAIM**

The ornamental design for an exercise bike with a high front bar as shown and described.

DESCRIPTION

FIG. 1 is a perspective view of an exercise bike with a high front bar.

FIG. 2 is a right side elevation view, the left side being a mirror image thereof;

FIG. 3 is a front elevation view thereof.

FIG. 4 is a rear elevation view thereof.

FIG. 5 is a top plan view thereof; and,

FIG. 6 is a bottom plan view thereof.

The broken lines show portions of the exercise bike with a high front bar that form no part of the claimed design.

1 Claim, 4 Drawing Sheets
